CLOCK

Pennie R. Ayres, Roanoke, Va.

Application March 17, 1933, Serial No. 661,359

7 Claims. (Cl. 58—38)

This invention relates to clocks, particularly to striking mechanism therefor, and the objects of the invention are:

To provide a striking mechanism which shall be simple and cheap to construct, composed of very few parts and which is readily adaptable to assembly in quantity production without the necessity of delicate hand adjustment of any of the parts.

It is also an object to provide a striking mechanism particularly adapted to synchronous motor electric clocks and to provide a novel control means for taking power from the synchronous motor to drive the striking mechanism.

Further objects and advantages of the invention will be apparent from the following description, reference being had to the accompanying drawing, wherein:

Fig. 1 is a front view of a clock constructed according to the present invention and on which the dial and hands are not shown for the sake of clearness.

Fig. 2 is a detail view showing a part of the invention which is attached to the hour wheel of the clock.

Fig. 3 is a partial detail view of parts of the invention forming a unitary assembly, the view being taken from the back.

Fig. 4 is a cross section on line 4—4 of Fig. 1.

Fig. 5 is a top view partly in section of the power take-off control mechanism.

Fig. 6 is a perspective view showing the mechanism attached to the hour wheel.

Fig. 7 is a perspective view showing the tripping mechanism.

Fig. 8 is a perspective view showing the power take-off control mechanism.

Fig. 9 is a perspective view of a part of the striking head.

In constructing a striking mechanism particularly adapted for a synchronous motor electric clock it is desirable to provide a simple and yet reliable construction. The striking mechanisms which have so far appeared on the market embodied in synchronous motor electric clocks have been largely patterned after the known types of spring driven striking mechanisms and include a complete gear train for driving the striking mechanism. In accordance with the present invention

there is provided a striking mechanism which is driven from the time train of a clock and in which simple but reliable means are provided for controlling the driving of the striking mechanism from the time train of a synchronous motor clock.

In distinction from other clocks in which the

striking mechanism is driven from the synchronous motor through clutches or shiftable gears the present device provides a constantly rotating member driven by the synchronous motor and which is adapted to oscillate the tail of a lever, 5 and connection between the rotary member and the lever is established by moving the lever into and out of the path of the rotary member.

The preferred form of the invention also embraces a novel mechanism for determining the 10 number of strokes at any hour which is considerably simpler and more reliable than the usual count wheel or rack and snail. There is provided a rotary member mounted concentrically to the hour wheel and which is adapted to be released 15 from its starting position once each hour. The motion of this wheel when released is limited by the position of the hour wheel itself by means of cooperating stops mounted on the member and the hour wheel respectively. Means is provided 20 for permitting movement of the hour hand through the position in which the stops would otherwise interfere with each other without in any way affecting proper operation of the striking mechanism.

Referring now to Fig. 1, there is shown a clock having the frame plate 2 which carries the usual synchronous motor and time train, the latter driving the minute shaft 4 and the hour sleeve 6. A bridge member 8 is secured to the front of the plate 2 in spaced relation by means of suitable fastenings 10 and carries fixed thereto a sleeve 12. Mounted on the sleeve 12 for free rotation thereon is a toothed wheel 14 having one short tooth 16 for a purpose to be later mentioned. 25 Pivoted on the plate 8 at 18 is a control lever 20 having a hole 21 formed therein for permitting limited oscillation about the pivot 18. The toothed wheel 14 is mounted on the sleeve 12 by means of a hub member 22 having a flange 24 at 30 its rear end which is spaced from the wheel 14. Between the flange 24 and the wheel 14 a spiral spring 26 is located having its inner end fastened to the hub 22 and its outer end secured to a post 28 mounted in the plate 8. The wheel 14 and its hub 22 are secured on the sleeve 12 by suitable fastening means such as the ring 30 pressed on the back end of the sleeve 12. Similar means are provided such as the ring 32 for securing the wheel 14 to the hub 22. A spring member 34 is 35 fastened to a post 36 secured to the plate 8 and has its opposite end bearing against the lever 20 to bias its top end to the right in Fig. 1. The plate 8, sleeve 12, wheel 14, control lever 20 and the associated parts just described are adapted to be 40 45 50 55

assembled together as a unit for ready attachment to the remainder of the clock mechanism. The time train of the clock includes the usual dial gears 38, 40, 42 and 44, the latter of which is the hour wheel and is provided with two diametrically opposed longitudinal slots 46. On the front face of the hour wheel 44 there is attached by means of suitable rivets 48 extending into the slots 46 a sliding stop member 50 carrying a boss 52 thereon projecting to the front of the plane of the stop slide 50. One end of the slide has a rounded nose 54 adapted to cooperate with a fixed cam 56 secured to the main frame plate 2 for the purpose of camming the stop slide 50 to the left 5 in Fig. 2 during a certain portion of the rotation of wheel 44. A spring 55 urges the slide 50 to the right in Fig. 2. The wheel 14 carries on the back face of its hub flange 24 a stop pin 53 which is spaced from the axis of the wheel 14 a sufficient 10 distance to enable it to meet the flat face of the stop lug 52 when the boss 52 and slide 50 are moved to the full extent of their movement to the right in Fig. 2, but enabling the pin to pass the boss 52 when it lies in the position to the left shown in 15 Fig. 2. The front face of the wheel 14 carries a pin 57 adapted to cooperate with a lug 58 formed on the control lever 20 whereby the wheel 14 when moving counterclockwise into its position of rest 20 may move the control lever 20 also counterclockwise. A shaft 60 projecting through the frame 25 plate 2 is geared at its inner end to the clock motor by gearing, not shown, which may include part of the time train and carries a disk 62 which carries on its forward face a series of projections 30 or pins 64. The number and the spacing of the pins 64 are chosen in such correlation with the speed of the rotary member 60 that one pin will pass a given point in about the interval desired between strokes of the striking hammer. A hammer arm 66 is secured to a shaft 68 pivoted in the 35 frame plate 2 which carries fixed thereto a short lever 70 and a light tail lever 72 mounted to permit a limited amount of front and back motion of the tail end of the lever 72. A spring member 74 normally urges the lever 72 up in Fig. 5 into 40 engagement with the pins 64. The top of the lever 72 is formed with a projecting flange 76 which is interrupted by a slot 78 at one portion. A pin 80 is secured in the outer end of the lever 45 72 and passes through a hole 82 in the lever 72 to prevent rotational movement of the lever 72 on the shaft 68. A bell crank 84 is pivoted at 86 on the frame plate 2 and has a slot 88 formed in one arm to receive a pin 90 secured to the lever 50 70 for interconnecting the bell crank and the lever 70. The other arm of the bell crank lever 84 carries a pivoted spring pressed pawl 92 having a pin 94 at its nose adapted to engage the teeth 55 of the wheel 14 for stepping the same back to the position of rest. The control lever 20 carries at 60 its lower end a projecting portion 96 having a beveled cam surface 98 adapted to force the lever 72 out of the path of the pins 64 when the control lever 20 lies in the position shown in Fig. 1 and the lever 72 moves upwardly in Fig. 1. The upper 65 end of the cam surface has a notch 100 formed therein adapted to receive the flange 76 when the lever 72 is in its fully raised position, as shown in Fig. 1. Tripping means is provided for controlling the operation of the mechanism so far described at predetermined times, such as at the hour and half hour. The minute shaft 4 carries rigidly therewith behind the pinion 38 a trip cam 102. A trip lever is pivoted at 104 and comprises 70 a cam follower arm 106 cooperating with the cam 78

102 and a tripping arm 108. The cam 102 has two tripping noses, the long one 110 passing under the arm 106 at the hour and a short one 112 passing under the arm 106 at the half hour. The outer end of the arm 108 is formed with a return portion carrying a pin 114 which acts as a holding latch for the wheel 14. A pawl 116 is pivoted at 118 to the arm 108 and has a pin 120 adapted to limit the clockwise rotation of the pawl 116 under the urge of the spring 122. A stop face 124 on the pawl 116 cooperates with the nose 126 on the upper end of the control lever 20 in preventing clockwise rotation of the control lever 20 when the arm 108 is in the raised position. On the hammer arm 66 there is mounted a hammer head 15 which is comprised of a body member 128, shown in perspective in Fig. 9, having a hole 130 therethrough adapted to receive the arm 66 and having a slightly tapered reduced end portion 132 and an internal bore 134. The reduced portion 132 may 20 be slotted, as shown in Fig. 9. A collar 136 has a bore tapered to fit the portion 132 snugly and in assembly is driven onto the portion 132 in order to clamp the striking leather 138 in the bore 134 and to clamp the head 128 to the arm 66. 25

In the operation of the mechanism thus far described it will be seen that the wheel 14 is normally held in the starting position, as shown in Fig. 1, by the pin 114 on arm 108, the spring 26 being fully wound when the wheel 14 is in this 30 position. The pin 57 on wheel 14 holds the control lever 20 in its normal position, as shown in Fig. 1, in which it is moved to the limit of its motion in a counterclockwise direction against a suitable stop 129, and in which the projecting portion 96 at the bottom of the control lever 20 lies in contact with the flange 76 on the lever 72 at the notch 100. When the minute hand next passes through the hour position the long nose 110 on the cam 102 raises the arms 106 and 108 40 of the tripping lever sufficiently to permit the pin 114 to clear all of the teeth on the wheel 14, while at the same time the stop face 124 of the pawl 116 moves up into cooperation with the lug 126 at the top of control lever 20. This permits the wheel 45 14 to rotate clockwise under the urge of the spring 26. The amount of this rotation is limited by the stop pin 53 which is mounted on the rear 50 face of flange 24 as it comes into contact with the flat face of the boss 52 on the stop slide 50, at all times except when the stop slide is cammed to the left in Fig. 2 by cam 56. It will then be seen that the amount of rotation of the wheel 14 is determined by the position of the hour wheel 44 since the position of the boss 52 determines the 55 point at which the stop pin 53 will stop further rotation of the wheel 14. As the lever 106 drops from the nose 110, at the hour, the stop face 124 falls from the path of the lug 126 and permits the spring 34 to move the control lever 20 clockwise 60 against a stop, not shown, inasmuch as the pin 57 is now out of the way of the lug 58 due to the initial rotation of the wheel 14. The clockwise movement of the lever 20 moves the projection 96 of the lever off from the flange 76 and opposite 65 the slot 78 so that the lever 72 is now permitted to move inwardly into the path of the pins 64 under the urge of the spring 74. Inasmuch as the rotary member 60 is constantly driven by the synchronous motor the pins 64 will each depress 70 the lever 72 until they pass off from the end of the same, as shown in Fig. 8, with the consequent oscillation of the shaft 68 and hammer lever 66, thus causing the hammer to strike a sounding element 140. At each oscillation of the lever 72 the 75

bell crank 84 is also oscillated simultaneously therewith through the pin 90 and slot 88. This causes the pawl 92 and pin 94 to step the wheel 14 in a counterclockwise direction, one step for each stroke of the hammer. Inasmuch as there are twelve teeth on the wheel 14 it will be seen that the number of strokes will be equal to the numeral of the hour at which the hour hand stands at each operation of the mechanism. At the last stroke of the hammer for any hour as the wheel 14 moves into its position of rest, the pin 57 moves the control lever 20 counterclockwise in Fig. 1. Inasmuch as arm 108 will be raised due to passing over the tooth 16 at the time, the pivoted pawl 116 will permit the lug 126 to move to the left over the nose of the pawl 116 and when it has passed over the same will return to the position illustrated under the urge of the spring 122. It will also be noted that at the time the control lever 20 moves into its normal position the arm 72 will be at the bottom of its stroke and will not be cammed out of the path of the pins 64 until the arm 72 is released from the pin 64 and is thus raised under the urge of the spring 142. At twelve o'clock the boss 52 would come into the position occupied by the pin 53. At this time, however, the cam 56 moves the slide 59 and boss 52 to the left in Fig. 2, thus removing the boss 52 from the path of the stop pin 53. When the wheel 14 is released at twelve o'clock the rotation of the same is limited, not by the stop pin 53 and boss 52, but by the pin 57, which, after the wheel 14 has made nearly a complete revolution, comes in contact with the opposite face of the lug 58, thus limiting the rotation of the wheel 14 to nearly one revolution. At the time the arm 106 drops off from the nose 110 the lever 20 rotates clockwise a small amount, as previously described, and this permits a slight further rotation of the wheel 14, thus allowing for a complete revolution of the wheel 14 at twelve o'clock. The short nose 16 on the first tooth of the wheel 14 is for the purpose of conveniently striking each half hour by a single stroke. At the half hour the short nose 112 on the cam 102 comes under the arm 106 and raises it sufficiently for the pin 114 to clear tooth 16, but not sufficiently to clear the next tooth on wheel 14, thus permitting the wheel 14 to move but one step. At the same time the stop face 124 engages the lug 126, holding lever 20 against movement until arm 106 drops off from the nose 112, as previously described. The operation at the half hour is otherwise identical with that taking place when the hour hand stands at one o'clock.

It will be noted that if at any time between striking periods an attempt should be made to manually lift the hammer 128, the flange 76 will engage the bottom face of the notch 100 and prevent sufficient motion of the hammer and related parts to permit engagement of the lever 12 with pins 64. This is to prevent accidental stoppage or other interference with the synchronous motor by lifting the hammer. It is possible with the present device to manually set the hands either forward or backward as fast or as slowly as desired without in any way interfering with the striking mechanism. There is provided on the cam 102 a recessed camming portion 144 at each operating nose 110 and 112 which engages with the lever 106 to cam the same outwardly to the front face of the cam 102 whenever the hand is rotated backward, the arm being sufficiently resilient to permit this operation. The striking mechanism is self-synchronizing at every hour

inasmuch as, if at any time the wheel 14 is displaced from its position of rest due to setting of the hands, it will be returned to the position of rest as soon as the synchronous motor is started and at the next hour the striking operation will 5 take place, as previously described.

It will be seen, therefore, that the invention provides a striking mechanism composed of few and comparatively rugged parts and which require no delicate adjustments. The mechanism 10 is particularly adapted to synchronous motor electric clocks. It is not limited in its application thereto inasmuch as the rotating member which oscillates the hammer lever may be driven from any other suitable source of power instead 15 of from the synchronous motor, as will be obvious to those skilled in the art. The invention also provides a striking mechanism which is readily assembled and parts of which may be constructed 20 as unitary sub-assemblies for later assembly 20 onto the other parts of the clocks without requiring any adjustment of the parts after or during assembly.

I claim:

1. In a striking clock including a time train 25 and a hand arbor driven thereby, the combination of a rotary member mounted concentric to said arbor, energy storing means urging said member in one direction of rotation, power driven means adapted to rotate said member in the opposite direction, a pair of cooperating stops operatively connected to said arbor and member respectively, and adapted to variably limit the rotation of said member in the one direction in accordance with the position of the hand arbor, 30 means normally preventing rotation of the member in one direction and for releasing it at predetermined times, and means for controlling the operation of the power driven means.

2. In a striking clock including a time train 40 and a hand arbor driven thereby, the combination of a rotary member mounted concentric to said arbor, energy storing means urging said member in one direction of rotation, power driven means adapted to rotate said member in the opposite direction, a pair of cooperating stops operatively connected to said arbor and member respectively, and adapted to variably limit the rotation of said member in the one direction in accordance with the position of the hand arbor, 45 means normally preventing rotation of the member in one direction and for releasing it at predetermined times, means for controlling the operation of the power driven means, and means for withdrawing one stop out of the path of the other when the hand arbor is moved through the position in which said stops would interfere with each other while the rotary member lies in its normal position of rest.

3. In a striking clock including a time train 60 and a hand arbor driven thereby, the combination of a rotary member mounted concentric to said arbor, energy storing means urging said member in one direction of rotation, power driven means adapted to rotate said member in the opposite direction, a pair of cooperating stops operatively connected to said arbor and member respectively, and adapted to variably limit the rotation of said member in the one direction in accordance with the position of the hand arbor, 65 means normally preventing rotation of the member in one direction and for releasing it at predetermined times, means for controlling the operation of the power driven means, and means for withdrawing one stop out of the path of the 70 other when the hand arbor is moved through the position in which said stops would interfere with each other while the rotary member lies in its normal position of rest.
